LIQUID FUEL BURNER APPARATUS

David C. Bortner, York, Pa., assignor to York-Shipley, Inc., York, Pa., a corporation of Delaware

Application May 17, 1944, Serial No. 535,982

6 Claims. (Cl. 158—28)

The present invention relates to burners for fluid fuels, such as gas and oil, wherein the fuel is delivered from a nozzle into a stream of air and ignited by means of electrodes supported in close proximity to the nozzle.

In burners of this type it is customary to provide a draft tube through which air is forced for combustion of the fuel, the fuel pipe extending longitudinally through said tube with the nozzle located at the furnace end thereof. There is also located within the tube an air directing or deflecting member having spirally arranged blades or vanes for imparting a whirling or gyroscopic motion to the forced air supply prior to its mixture with the fuel at the nozzle, and electric means for igniting the mixed air and fuel.

The primary object of this invention is to provide improved means for mounting the igniting electrodes in the blades or vanes of the air deflecting member.

Another object of the invention is to support the igniting electrodes in the blades or vanes in such a manner that they do not affect or interfere with the whirling or gyroscopic motion imparted to the air by contact thereof with the air directing member.

A further object of the invention is to clamp or lock the igniting electrodes in the vanes of the air deflector by means of a wedge-like member positioned between two adjacent vanes, the ends of which are urged into binding contact with the electrodes.

A still further object of the invention is to provide means for locking the air deflecting member to the fuel pipe simultaneously with the securing of the igniting electrodes in the deflecting vanes.

Other objects and advantages of this invention will be apparent from the following description of the embodiment of the invention illustrated in the accompanying drawing in which:

Figure 1 is a plan view, partly in section, of the furnace end of a liquid fuel burner embodying the features of the present invention.

Fig. 2 is a cross-sectional view taken substantially on line 2—2 of Fig. 1.

Fig. 3 is an elevational view, partly in section, of the wedge employed for locking the electrodes in the air deflecting vanes.

Fig. 4 is a top plan view of the wedge shown in Fig. 3.

Fig. 5 is a cross-sectional view through the wedge taken substantially on line 5—5 of Fig. 3.

Referring to the drawing for a more detailed description thereof, the fuel nozzle of a liquid fuel burner device is indicated by the reference numeral 10, which nozzle is threadedly secured to a fuel pipe 11 at the furnace end thereof. The fuel pipe 11 is centrally arranged and supported within an air supply conduit or tube 12, the lat-

ter having a nose piece 13 threadedly secured thereto as indicated at 14. As is to be understood, the fuel pipe 11 is suitably supported at the end of the tube 12 opposite the nose piece 13, the same being preferably carried in brackets or the like formed in the end of the tube 12 in a manner well known, whereby said fuel pipe is centrally positioned within the tube 12 in a relatively stationary manner.

10 As before indicated, burners of this character usually include an air directing or deflecting member which functions to impart a whirling or gyroscopic motion to the air about the fuel nozzle whereby to insure uniform distribution of the

15 air about the emerging spray of fuel. In accordance with the present invention there is provided an air directing or deflecting member indicated generally by the reference numeral 15, the same comprising a hub portion 17 having a central aperture 18 through which the fuel pipe 11

20 extends. When initially positioning the member 15 within the tube 12 it is readily slidable on the fuel pipe 11 until properly spaced from the nozzle 10, the diameter of the central aperture 18 being slightly greater than the outer diameter

25 of the fuel pipe 11 to permit this slidable movement, as is seen from an inspection of Fig. 2 of the drawing. The member 15 is subsequently locked on the fuel pipe 11 in a manner to be 30 hereinafter described. Radiating from the hub 17 is a series of vanes or blades 19, 20, 21 and 22, having spiral surfaces to impart the necessary whirling motion to the air being forced through the tube 12 and coming in contact with

35 the vanes.

In the fabrication of the member 15, each of the vanes 21 and 22 is formed with a relatively large section 23 and 24 having a central bore 25 and 26 respectively, for the reception of the igniting electrode insulators 27 and 28. The insulators 27 and 28 are freely movable in the bores

30 and 26 when initially assembling the device, and as will hereinafter appear, a means has been provided for clamping each electrode in its respective vane.

The high tension electrical igniting means for the burner includes a pair of metal leads or busbars 29 which terminate adjacent the discharge end of the nozzle 10, to provide an electric spark

40 gap 30. The numerals 27 and 28, as before indicated, designate a porcelain or similar insulating medium for the leads 29 and it is this insulating portion which is supported within the air deflecting member 15. Current is supplied to the

45 leads 29 in a manner well known in this art.

In accordance with the present invention, a means has been provided for releasably retaining the insulators 27 and 28 within the vanes 21 and 22 and, by referring more particularly to Fig.

50 2 of the drawing, it will be noted that a portion

of the hub 17 and vanes 21 and 22 is formed with an arcuate-shaped slot 31 which communicates with the hub aperture 18. This slot 31 is adapted to have positioned therein an arcuate-shaped wedge-like member 32 having beveled ends 33 and 34 adapted to be forced into binding contact with the insulators 27 and 28. The member 32 is provided with a central threaded bore 35 for receiving an exteriorly threaded locking screw 37. When desiring to clamp the insulators 27 and 28 after they have been properly spaced from the nozzle 10 and positioned within the vanes 21 and 22, the locking screw 37 is turned downwardly within the aperture 35 until contact is made with the fuel pipe 11. This initial contact of the locking screw with the fuel pipe will fasten the member 15 on said fuel pipe to preclude further movement thereof. Further turning of the screw 37 into contact with the pipe 11 will raise the arcuate-shaped member 32 until its ends 33 and 34 are brought into contact with and securely clamp or bind the insulators 27 and 28 within their openings 25 and 26, respectively.

From the foregoing description when taken in connection with the accompanying drawing, it will be readily apparent that a novel means has been provided for adjustably supporting and clamping the electrodes of an ignition system in the vanes of an air deflecting member while simultaneously locking the deflecting member on the fuel pipe. When desiring to remove the insulators 27 and 28 from the vanes 21 and 22, the operation just described is reversed in that the screw 37 is moved out of the opening 35 permitting the arcuate-shaped member 32 to move away from the electrodes 27 and 28. The relation of the member 32 and slot 31 is such that the former is capable of limited movement, it merely being necessary to screw the threaded member 37 downwardly through the opening 35 until contact is made with the fuel pipe 11 and upon further movement of said screw the member 32 will be raised so that its ends 33 and 34 will engage the insulator 27 and 28 in the manner previously described.

Other advantages of my improved apparatus will be readily apparent from the above description thereof. Obviously, variations in the nature and arrangement of the elements described will be evident to those skilled in this art, and this invention contemplates any equivalent structure within the scope of the following claims.

I claim:

1. In a liquid fuel burner of the class described, the combination with a fuel nozzle, and a fuel pipe extending to and supporting said nozzle, of an air deflecting member and electrode support, said air deflecting member having a central hub portion fitting about said fuel pipe, a series of vanes radiating from said hub portion, a pair of electrode insulators adjustably supported in certain of said vanes, and a single means comprising relatively movable parts for securing said air deflecting member on said fuel pipe and simultaneously clamping said electrode insulators in said certain vanes.

2. In a liquid fuel burner of the class described, the combination with a fuel nozzle, and a fuel pipe extending to and supporting said nozzle, of an air deflecting member and an electrode insulator support, said air deflecting member having a central hub portion fitting about said fuel pipe, a series of vanes radiating from said hub portion, apertured enlarged portions in certain of said

vanes for supporting an igniting electrode insulator, and means for clamping said electrode insulator in said apertured enlarged portions and simultaneously clamping said air deflecting member on said fuel pipe.

3. In a liquid fuel burner of the class described, the combination with a fuel nozzle, and a fuel pipe extending to and supporting said nozzle, of an air deflecting member and electrode support, 10 said air deflecting member having a central hub portion fitting about said fuel pipe, a series of vanes radiating from said hub portion, a pair of electrode insulators adjustably supported in certain of said vanes, and a member including electrode insulator-engaging portions and a relatively movable fuel pipe-engaging member disposed between said vanes and said hub adapted to simultaneously clamp each of said electrode insulators in said certain vanes and secure said hub 15 on the fuel pipe.

4. In a liquid fuel burner of the class described, the combination with a fuel nozzle, and a fuel pipe extending to and supporting said nozzle, of an air deflecting member and electrode support, 20 said air deflecting member having a central hub portion fitting about said fuel pipe, a series of vanes radiating from said hub portion, a pair of electrode insulators adjustably supported in certain of said vanes, and means disposed between 25 said vanes and hub portion adapted to clamp said electrode insulators in said certain vanes, said means cooperating with said electrode insulators and said fuel pipe to secure said deflecting member on said fuel pipe with the clamping 30 of said electrodes.

5. In a liquid fuel burner of the class described, the combination with a fuel nozzle, and a fuel pipe extending to and supporting said nozzle, of an air deflecting member and electrode support, 35 said air deflecting member having a central hub portion fitting about said fuel pipe, a series of vanes radiating from said hub portion, an electrode insulator supported in each of a pair of said vanes, said pair of vanes and hub portion being 40 formed with a slot exposing a portion of said electrode insulators and a member positioned in said slot for clamping said electrode insulators in said pair of vanes.

6. In a liquid fuel burner of the class described, 45 the combination with a fuel nozzle, and a fuel pipe extending to and supporting said nozzle, of an air deflecting member and electrode support, said air deflecting member having a central hub portion fitting about said fuel pipe, a series of 50 vanes radiating from said hub portion, an electrode insulator supported in each of a pair of said vanes, said pair of vanes being each provided with a bore for adjustably receiving said electrode insulators, said pair of vanes and hub portion 55 being also formed with an arcuate-shaped slot opening into said vane bores and exposing a portion of said fuel pipe and said electrode insulators, an arcuate-shaped member within said slot having divergent ends which extend toward 60 said electrode insulators, and a threaded clamping member carried by said arcuate-shaped member adapted to be moved into contact with said fuel pipe for clamping said deflecting member thereto and simultaneously raising said arcuate-shaped member to urge the ends thereof into clamping engagement with said electrode insulators.

DAVID C. BORTNER.
